PEEP SIGHT FOR FIREARMS

Bryce Poe, Kansas City, Mo.

Application March 28, 1947, Serial No. 737,863

5 Claims. (Cl. 33—56)

1

This invention relates to a novel construction of peep sight for firearms and more especially to a peep sight adapted to be used as the rear sight for rifles.

More particularly, it is among the objects of the present invention to provide an improved rear peep sight for rifles which is extremely rugged so that it is virtually impossible to accidentally damage the sight; which is very compact regardless of the setting thereof; which readily adapts itself to precision production and close tolerances thereby reducing possible mechanical errors to a minimum; which, after adjustment can not be accidentally moved out of adjustment or the adjustment thereof changed without the use of a special tool, thus substantially locking the sight in adjustment against unauthorized tampering therewith, and which is capable of being accurately adjusted by a single adjustment for making corrections for elevations and deflection or windage.

Still another object of the invention is to provide a substantially enclosed peep sight which will afford a smooth exterior, irrespective of the setting thereof, to thereby obviate any possibility of any of the moving parts of the sight striking an obstruction such as the interior of a saddle boot, a weapon's case, clothing or brush, and to provide a sight having no projecting knobs or other extensions capable of catching on obstacles, so that a particular sight setting may be maintained indefinitely and under corresponding conditions of terrain, wind and light, may be utilized at spaced time intervals and without requiring resetting of the sight, or only a partial resetting thereof.

Various other objects and advantages of the invention will hereinafter become more fully apparent from the following description of the drawing, illustrating a preferred embodiment of the invention, and wherein:

Figure 1 is a side elevational view, partly in longitudinal section showing a preferred embodiment of the improved peep sight;

Figure 2 is a rear elevational view thereof, showing the peep sight applied to a portion of the upper part of a firearm receiver;

Figure 3 is a view similar to Figure 2 but looking toward the forward end of the peep sight;

Figure 4 is a side elevational view, partly in longitudinal section of the inner cylinder of the peep sight;

Figure 5 is a side elevational view of the outer cylinder thereof, and

Figure 6 is an exploded perspective view of the inner and outer cylinders and their connecting elements.

2

Referring more specifically to the drawing, the peep sight in its entirety, constituting the invention, is designated generally 1 and constitutes generally a housing section 8, an outer cylinder 9 and an inner cylinder 10.

The housing section 1 comprises an elongated base 11 and an integral barrel or cylinder portion 12 which is disposed thereabove and longitudinally thereof and which is provided with a bore 13 of circular cross section and which extends longitudinally therethrough. The base 11 is provided with an undersurface 14 which is shown as being concave in cross section to rest flush on the rounded upper side of the receiver or barrel 15 of a rifle or other suitable firearm, not shown. It will be readily apparent that the undersurface 14 could be of various shapes to conform to the contour of the upper surface of any receiver or barrel on which it is adapted to be mounted.

The base 11 extends beyond the ends of the barrel or cylinder portion 12 and is provided adjacent each end thereof with an upwardly flared opening 16 for receiving the flared head of a screw fastening 17 each of which extends into a threaded upwardly opening recess 18 in the receiver or barrel 15 for detachably mounting the peep sight 1 thereon. When the fastenings 17 are tightened, the heads thereof will not extend above the upper surface of the base 11 and said fasteners will cooperate to retain the under surface 14 of base in flush engagement with the upper surface of the barrel or receiver to thereby securely attach the peep sight 1 thereto.

The outer cylinder 9, which is of circular cross section externally, is sized to slidably and rotatably engage in the bore 13 and is provided with an eccentrically disposed bore 19 which extends longitudinally therethrough and which the inner cylinder 10 is sized and shaped to slidably and rotatably engage. The outer cylinder 9 is provided with a diametrically disposed bore 20 formed in the thickened portion thereof and adjacent the forward end of said cylinder 9 and which has an inner end opening into the bore 19 and an outer end which opens outwardly of the periphery of said cylinder to receive a pin 21 which is of a length greater than that of the bore 20. The cylinders 9 and 10 are of approximately the same length and when the cylinder 10 is applied to the bore 19 and with the ends thereof disposed flush with the ends of the cylinder 9, the inner end of the pin 21 will seat in a portion of an annular, outwardly opening groove or channel 22 of the inner cylinder 10 for rotatably connecting said cylinders 9 and 10.

As best seen in Figure 1, the barrel or cylinder portion 12 is provided with an annular groove or

channel 23 which opens inwardly into the bore 13 thereof and said barrel 12 is provided with a longitudinally disposed, inwardly opening groove 24 having an inner end communicating with the annular groove 23 and an outer end opening outwardly of the forward end of said cylinder portion 12. The outer end of the pin 21 projects beyond the periphery of the outer cylinder 9, when the inner end thereof is seated in the groove 22, said outer end is adapted to be received in the groove 24 for permitting the connected cylinders 9 and 10 to be inserted into the bore 13 through the forward end of said cylinder or barrel 12 and so that said outer end of the pin 21 may thus be moved into engagement with the groove 23, so that by rotation of the cylinders 9 and 10, said cylinders will be rotatably engaged with the barrel 12. Thus it will be readily apparent that the ends of the pin 21 will be retained in engagement with the grooves 22 and 23 so as to turnably and non-slidably mount the cylinder 9 in the housing 8 and the cylinder 10 in said cylinder 9.

The inner cylinder 10 is provided with an eccentrically disposed peep sight bore 25 which extends longitudinally therethrough and which is provided with a restricted portion 26, disposed contiguous with the groove 22 thereof.

As best seen in Figure 3, the forward end of the cylinder 9 is provided with spaced tool receiving recesses or sockets 27 and the complementary end of the cylinder 10 is provided with a single tool receiving recess or socket 28, which is diametrically spaced from its bore 25.

The opposite end of the cylinder 9 is provided with circumferentially spaced, longitudinally extending slots 29, each of which opens into the bore 19 and outwardly of the periphery of said cylinder 9 and each of which extends to the rear end of the cylinder, as best illustrated in Figure 6. The base portion of the housing section 8 and adjacent portion of the barrel part 12 thereof are provided, on opposite sides of said section 8, with inwardly extending threaded bores 30, formed by drilling transversely through the section 8 and internally threading the ends of the drilled bore. The upper part of the intermediate portion of the drilled bore opens into the bore 13, as seen at 31. Each threaded portion 30 is adapted to receive an Allen type set screw 32 having a conical inner end 33, received in the complementary bore portion 31 and which, when advanced, extends into the bore 13 for clamping engagement with the cylinder 9 for fixedly securing said cylinder against rotation within the bore 13. The set screws 32 also compress the slotted end of the cylinder 9 for clamping the inner cylinder 10 within the bore 19 and against rotation relatively thereto.

Assuming that the peep sight 7 is applied and assembled in the manner as previously described, and as illustrated in the drawings, and that the cylinders 9 and 10 are arranged, as seen in Figures 2 and 3, corrections in elevation and/or deflection may be made by moving the peep sight bore 25 relatively to the housing section 8 by rotating the inner cylinder 10 within the bore 19 sufficiently to move bore 25 the desired and necessary distance from the center of bore 13, after slightly loosening set screws 32, and then rotating the cylinders as a unit within bore 13 sufficiently to move the bore 25 to the desired and necessary direction from the center of bore 13, after further loosening set screws 32. The set screws 32 are loosened or tightened with a con-

ventional Allen type wrench, not shown, and a special wrench, not shown, provided with two prongs, one of which engages each of the sockets 27, may be employed for turning the cylinder 9 in the bore 13, and another two-prong wrench, having prongs arranged to engage the socket 28 and the bore 25, and which may constitute the opposite end of the aforementioned pronged wrench, may be employed for turning the inner cylinder 10 in the cylinder 9 for accomplishing the vertical or transverse displacement of the peep sight bore 25 from its central position of Figures 2 and 3.

It will thus be readily apparent that a peep sight of extremely simple construction is provided having no knobs or other projections capable of catching on clothing, brush, saddle boots or the like, and which is capable of being readily adjusted to compensate for elevations or deflections and which may be clamped in adjusted position so that the setting of the sight can not be tampered with or varied without the use of a special tool.

Various modifications and changes are contemplated and may obviously be resorted to, without departing from the spirit and scope of the invention as hereinafter defined by the appended claims.

I claim as my invention:

1. In a peep sight of the character described, an outer housing section provided with a longitudinal bore extending therethrough, an outer cylinder rotatably disposed in said bore and detachably contained therein, said outer cylinder having an eccentrically disposed bore extending longitudinally therethrough, an inner cylinder detachably mounted in said outer cylinder bore and rotatably retained therein, said inner cylinder being provided with an eccentrically disposed peep sight bore extending longitudinally therethrough, and said cylinders being rotatable as a unit or independently of one another for vertically or laterally displacing said peep sight bore relatively to the outer, housing section, said outer cylinder having a slotted end, and means for detachably clamping the outer cylinder to the housing and for contracting its slotted end for clamping the inner cylinder in the bore of said outer cylinder.

2. In a peep sight of the character described, an outer housing section having a base adapted to be detachably mounted on the barrel or receiver of a firearm and provided with a longitudinal bore extending therethrough, an outer cylinder rotatably disposed in said bore and detachably contained therein, said outer cylinder having an eccentrically disposed bore extending longitudinally therethrough, an inner cylinder detachably mounted in said outer cylinder bore and rotatably retained therein, said inner cylinder being provided with an eccentrically disposed peep sight bore extending longitudinally therethrough, and said cylinders being rotatable as a unit or independently of one another for vertically or laterally displacing said peep sight bore relatively to the outer, housing section, said outer cylinder being provided with a diametrically extending bore opening into the bore thereof and outwardly of its periphery, a pin of a greater length than said diametrical bore and slidably disposed therein, said inner cylinder having an annular groove for receiving the inner end of the pin, and said housing having an annular inwardly opening groove communicating with the bore thereof for receiving the outer end of the pin for rotatably connecting the parts.

2,456,214

5

3. In a peep sight of the character described, an outer housing section having a base adapted to be detachably mounted on the barrel or receiver of a firearm and provided with a longitudinal bore extending therethrough, an outer cylinder rotatably disposed in said bore and detachably contained therein, said outer cylinder having an eccentrically disposed bore extending longitudinally therethrough, an inner cylinder detachably mounted in said outer cylinder bore and rotatably retained therein, said inner cylinder being provided with an eccentrically disposed peep sight bore extending longitudinally therethrough, and said cylinders being rotatable as a unit or independently of one another for vertically or laterally displacing said peep sight bore relatively to the outer, housing section, said outer cylinder being provided with a diametrically extending bore opening into the bore thereof and outwardly of its periphery, a pin of a greater length than said diametrical bore and slidably disposed therein, said inner cylinder having an annular groove for receiving the inner end of the pin, and said housing having an annular inwardly opening groove communicating with the bore thereof for receiving the outer end of the pin for rotatably connecting the parts, and said housing having a longitudinally extending groove opening outwardly of one end thereof and into its inwardly opening groove, through which the outer end of said pin is movable for applying and removing the cylinders relatively to the housing.

4. In a peep sight of the character described, an outer housing section having a base adapted to be detachably mounted on the barrel or receiver of a firearm and provided with a longitudinal bore extending therethrough, an outer cylinder rotatably disposed in said bore and detachably contained therein, said outer cylinder having an eccentrically disposed bore extending longitudinally therethrough, an inner cylinder detachably mounted in said outer cylinder bore and rotatably retained therein, said inner cylinder being provided with an eccentrically disposed peep sight bore extending longitudinally therethrough, and said cylinders being rotatable as a

6

unit or independently of one another for vertically or laterally displacing said peep sight bore relatively to the outer, housing section, one end of said outer cylinder being longitudinally slotted, and set screw means disposed in opposed relationship in said housing section and extending into the bore thereof for engaging the slotted end of the outer cylinder for clamping said outer cylinder relatively to the housing section and for compressing the slotted end thereof for clamping the inner cylinder therein.

5. In a peep sight of the character described, a base section adapted to be secured to a firearm receiver or barrel, an outer cylinder rotatably disposed in the base section, and an inner cylinder rotatably mounted in the outer cylinder and eccentrically thereof and provided with an eccentrically disposed peep sight bore extending longitudinally therethrough, said cylinders being rotatable within the housing section as a unit or independently of one another for vertically and/or laterally displacing the peep sight bore relatively to the housing section, said outer cylinder having a contractable portion, and means adjustably disposed in the housing section for clamping the outer cylinder thereto and for contracting said portion thereof to clamp the inner cylinder therein.
